[57] CLAIM

The ornamental design for an auto paint protector, as shown and described.

DESCRIPTION

FIG. 1 is a perspective view as seen from the top front and one side of an "auto paint protector" showing my new design;

FIG. 2 is a view in top elevation thereof;

FIG. 3 is a view in bottom elevation thereof;

FIG. 4 is a view in front elevation thereof;

FIG. 5 is a view in rear elevation thereof;

FIG. 6 is a view in left side elevation thereof; and,

FIG. 7 is a view in right side elevation thereof.
